(57) **CLAIM**

The ornamental design for an articulated pole for a mobile stand, as shown and described.

DESCRIPTION

FIG. 1 is an upper-right-front perspective view of an articulated pole for a mobile stand in accordance with the present design;

FIG. 2 is a lower-left-back perspective view of the articulated pole for a mobile stand shown in FIG. 1;

FIG. 3 is a front view of the articulated pole for a mobile stand shown in FIG. 1;

FIG. 4 is a back view of the articulated pole for a mobile stand shown in FIG. 1;

FIG. 5 is a top plan view of the articulated pole for a mobile stand shown in FIG. 1;

FIG. 6 is a bottom plan view of the articulated pole for a mobile stand shown in FIG. 1;

FIG. 7 is a left side view of the articulated pole for a mobile stand shown in FIG. 1; and,

FIG. 8 is a right side view of the articulated pole for a mobile stand shown in FIG. 1.

1 Claim, 6 Drawing Sheets
